UNITED STATES PATENT OFFICE.

FERDINAND ANLIKER, OF SHARON, PENNSYLVANIA, AND RUSSELL J. WITTMER, OF CLEVELAND HEIGHTS, OHIO, ASSIGNEES TO NATIONAL MALLEABLE AND STEEL CASTINGS COMPANY, OF CLEVELAND, OHIO, A CORPORATION OF OHIO.

CAR COUPLER.

Application filed June 6, 1925, Serial No. 35,346. Renewed August 25, 1927.

Fig. 1 is a plan, partly in section, of a pair of interlocked couplers embodying our invention, with the parts in locked position; Fig. 2 is an elevation, partly in section, with the parts as shown in Fig. 1, but with the head of the bolt removed; Fig. 3 is a plan, partly in section, but with the lock in lock-set position; Fig. 4 is an elevation, partly in section, with the parts in the position shown in Fig. 3; Fig. 5 is an elevation, partly in section, showing the position of the parts just after the lock has been released from lock-set position and lock and lever are free to drop to normal or lowermost positions; Figs. 6 and 7 show the operating lever in plan and side elevation, respectively; Fig. 8 is a side elevation of the lock; and Fig. 9 shows in elevation a modified form of lever.

Our invention relates to car couplers of the vertical plane type, such as are shown in Letters Patent of John Willison No. 1,201,665, dated October 17, 1916, in which the coupler comprises a coupler head, a lock, and a suitable actuating mechanism for the lock. The present invention comprises an improved means of retracting and lock-setting the lock, of releasing the lock from lock-set, and in so forming the lock, the lock operating mechanism and the cooperating parts of the coupler head that the movements of the lock into and out of lock-set position are extremely reliable and when in lock-set position remain in such position until intentionally dislodged therefrom. Our invention also comprises the various features which we shall hereinafter describe and claim.

Referring to the drawings, the coupler is comprised of a coupler head 2 having a buffing jaw 3, and a pulling jaw 4, connected by a buffing face 5 arranged on an axis inclined laterally to the line of draft. The pulling jaw has a laterally extending recess 4^a to receive the complementary jaw 3 of the opposing coupler head, and its pulling face 7 engages a complementary face 8 on the buffing jaw 3 of the opposing coupler head. The lock 9 of the coupler operates in a pocket or cavity 10, which extends upwardly and rearwardly from the buffing face 5 into the coupler head. The lock operates on the inclined bottom 11 of the cavity 10 and is closely confined in its movement by the side

walls 12 and 13, and may have on the side toward the wall 13 a lateral projection 14 which cooperates with an elongated recess 13^a in the wall 13. This projection and recess engagement between lock and wall 13 serves as an auxiliary guide for the lock in its movement and also may act as a limiting stop. The top face 15 of the lock is inclined 55 and parallel to the bottom face, and the downward projection 16 from the top of the coupler head cooperates with the face 15 to prevent the lock from being displaced vertically. The lock has an elongated recess 17 on its under side through which the transverse bolt 18 extends, the forward end of the recess acting as a stop to prevent the lock from being retracted too far into the coupler head and the rear end of the recess 17 acting 60 as a stop to prevent the lock from being projected too far out of the coupler head.

Mounted on the transverse bolt 18 is an operating lever 19 which is comprised of 75 two arms 20 and 20^a joined at their rear ends by the web 21, both of which are apertured for the bolt 18. The lock on the side toward the buffing jaw 3 has a recessed portion or cavity 22 into which the arm 20 of 80 the lever 19 extends. The forward end of the arm 20 terminates in a hook 23 which engages a projection 24 in the upper portion of the cavity in the lock. The arm 20 also has a cam face 25, which engages a cam 85 surface 26 to the rear of the projection 24 and upon actuation of the arm 20 causes the initial retraction of the lock, while the engagement of the hook 23 against the projection 24 causes its further retraction. This 90 cam action provides a powerful means for retracting the lock so that it is possible to unlock the couplers while under tension.

The actuating lever 19 has also a laterally extending shoulder 27, which when the lever 19 is in non-actuating position lies to the rear of the rear face of the lock and prevents the lock from being driven rearwardly—for instance, under impact coupling—into lock-set position, or from being 100 jammed into the rear of the pocket 10.

The lever arm 20^a extends outside the coupler head and the aperture 28 therein is of a diameter to accommodate the circular shoulder of the bolt head 29 upon which the arm 105 20^a rotates. Near the extremity of the arm

20^a is an opening 30 for an actuating member or uncoupling rod 31.

In assembling the parts the lock 9 is first placed in position in the lock cavity, the lever 19 is next put in position, and then the bolt 18 is slid through the apertures in the coupler head and lever 19, through the recess 17 in the lock, and, finally, the nut 18^a is applied. The lock thus can not be removed without first removing the bolt 18. To relieve the lever 19 and bolt 18 from blows from the lock during impact coupling a stop lug 33 is provided on the inner face of the wall 13, which is engaged by the shoulder 27 on the lever 19, and the blows which are received by the shoulder 27 from the lock are thus transmitted to the coupler head.

In the operation of our improved coupler, 20 the lock is normally in lowermost position, as is shown in Figs. 1 and 2. When it is desired to uncouple, the lever is turned on the bolt 18 in a counter-clockwise direction by means of the uncoupling rod 31. This rotates the arm 20 until its cam face 25 is in contact with the cam surface 26 of the lock and as the rotation of the arm 20 is continued, causes the lock to move upwardly and rearwardly until the hook 23 at the forward 30 end of the lever comes into contact with the projection 24, which causes the lock to be moved into its full retracted position preparatory to lock-setting.

When it is desired to place the lock 9 in lock-set position, a further rotation of the operating lever 20 causes the hook 23 to enter the cavity above the projection 24. Then, when the operating rod 31 is released, the lever 19 is held from falling back into 40 normal position by the engagement of the inner face of the hook 23 against the inclined upper face 24^a of the projection 24, which is struck at an angle so as to form a hooking engagement with the inner surface of the hook 23. It will thus be seen, as is shown 45 in Fig. 4, that after the lock has been elevated to uncoupled position, as the lock attempts to slide down by gravity to lowermost position, the face 24^a of the projection 24 wedges against the inner face of the hook and thus holds the lock in elevated or lock-set position. The opposing coupler is then 50 free to draw away. As the couplers draw apart the lock of the opposing coupler will engage the bevelled forward face 32 of the lock which is on lock-set and squeeze or move it slightly to the rear, thus raising the surface 24^a out of wedging engagement with the inner face of the hook, and the arm 20 55 of the lever, because of its over-balanced weight, will rotate downwardly and forwardly out of the way of the lock projection 24 and the lock is then free to drop into lowermost position, as is shown in Fig. 2. 60 Sometimes, however, as the couplers draw

apart there is a tendency to force the lock which is in locked position to the rear. To prevent this there is a small projection 17^a in the recess 17 on the lock, in such position that it bears against the bolt 18 when the lock is in locked position, which sufficiently retards the rearward movement of the lock when urged rearwardly, and by its resistance to rearward movement, causes the opposing lock on lock-set to be raised and thus released from lock-set position. 75

When opposing couplers come together, if one of the couplers happens to be on lock-set, the opposing lock strikes the lock on lock-set, and drives it slightly to the rear, 80 thus releasing the interlock between the projection 24 on the lock and hook 23 on the lever arm 20, which permits the arm 20 to rotate downwardly out of the way and leaves the lock free to drop into lowermost or 85 locked position.

Couplers constructed in accordance with our invention are extremely effective in coupling operations, because of the provisions for preventing the lock from being thrown into lock-set position or from being jammed into the rear of the coupler cavity. Even when couplings are made at comparatively high speed we have found that the protection against premature lock-setting is extremely 90 satisfactory and that the application of our invention has greatly improved the coupler. We have also found that interlocking engagement between the operating mechanism and the lock makes the lock-setting operation accurate and one which we have found to be very reliable in operation.

In Fig. 9 we have shown a modified form of lock operating lever which has an arc-shaped surface 34 immediately to the rear of the eye 30', which supports the actuating member 31', and considerably increases the leverage exerted by the member 31' in retracting the lock.

The terms and expressions which we have employed are used as terms of description and not of limitation, and we have no intention, in the use of such terms and expressions, of excluding any mechanical equivalents of the features shown and described, or portions thereof, but recognize that various structural modifications are possible within the scope of the invention claimed.

What we claim is:

1. A car coupler comprising two rigid, laterally separated oppositely disposed jaws having a longitudinally extending cavity therebetween; a lock movable in the cavity to assume a projected locking position, a retracted unlocking position and a lock-set position; a lock actuating member; and cooperating means on the said member and lock for supporting the lock in lock-set position. 120

2. A car coupler comprising two rigid, laterally separated oppositely disposed jaws 125

having a longitudinally extending cavity therebetween; a lock movable in the cavity to assume a projected locking position, a retracted unlocking position and a lock-set position; a lock actuating member; and cooperating means on the said member and lock for supporting the lock in lock-set position, the said member being arranged to move the lock into the retracted unlocking position and into lock-set position.

3. A car coupler comprising two rigid, laterally separated oppositely disposed jaws having a longitudinally extending cavity therebetween; a lock movable longitudinally in said cavity; lock-actuating means; and a projection and recess engagement between the lock and said means for supporting the lock in lock-set position.

4. A car coupler comprising two rigid, laterally separated oppositely disposed jaws having a longitudinally extending cavity therebetween; a lock movable in the cavity longitudinally of the coupler to assume a projected locking position and a retracted unlocking position; a lock actuating member having a portion thereof arranged in the path of the lock to prevent the lock from being driven out of operative position except under actuation from said member, said member and said lock having cooperative surfaces for supporting the lock in lock-set position.

5. A car coupler comprising two rigid, laterally separated oppositely disposed jaws having a longitudinally extending cavity therebetween; a lock movable in the cavity longitudinally of the coupler to assume a projected locking position and a retracted unlocking position; a lock actuating member having a portion thereof arranged in the path of the lock to prevent the lock from being driven out of operative position except under actuation from said member, said member and said lock having cooperative surfaces for supporting the lock in lock-set position, said lock being incapable of assuming lock-set position except on actuation by said actuating member.

6. A car coupler comprising two rigid lat-

erally separated oppositely disposed jaws having a longitudinally extending cavity therebetween; a lock movable in the cavity to assume a projected locking position and a lock-set position, said lock when in its projected locking position arranged to have an overlapping engagement with the lock of an opposing coupler; and a lock actuating member; the lock actuating member and the lock having cooperating cam-shaped surfaces which retract the lock to lock-set position.

7. A car coupler comprising two rigid, laterally separated oppositely disposed jaws having a longitudinally extending cavity therebetween; a lock movable in the cavity to assume a projected locking position, a retracted unlocking position and a lock-set position; and a lock actuating member; the lock actuating member and the lock having sets of cooperating cam-shaped surfaces by which the lock is actuated, one set of which supports the lock in lock-set position.

8. A car coupler comprising two rigid, laterally separated oppositely disposed jaws having a longitudinally extending cavity therebetween; a lock movable in the cavity to assume a projected locking position, a retracted unlocking position and a lock-set position; and a lock actuating member; the lock actuating member and the lock having sets of cooperating cam-shaped surfaces by which the lock is successively actuated, one set of which supports the lock in lock-set position.

9. A car coupler comprising two rigid, laterally separated oppositely disposed jaws having a longitudinally extending cavity therebetween; a lock movable in the cavity to assume a projected locking position, a retracted unlocking position and a lock-set position; a lock actuating member; and a through bolt upon which the lock rides; the lock also having means cooperating with the bolt for preventing the lock from moving into lock-set position as the lock draws away from a lock of an opposing coupler.
